UNITED STATES PATENT OFFICE

CHARLES H. WIDMAN, OF DETROIT, MICHIGAN, ASSIGNOR TO MURRAY CORPORATION OF AMERICA, OF DETROIT, MICHIGAN, A CORPORATION OF DELAWARE

DESIGN FOR A VEHICLE BODY

Application filed September 30, 1929. Serial No. 32,895. Term of patent 3½ years.

To all whom it may concern:

Be it known that I, CHARLES H. WIDMAN, a citizen of the United States, residing at Detroit, in the county of Wayne and State of Michigan, have invented a new, original, and ornamental Design for a Vehicle Body, of which the following is a specification, reference being had to the accompanying drawings, forming a part thereof, in which:

Fig. 1 is a side elevation of an automobile body embodying my design.

Fig. 2 is an enlarged perspective illustrating the formation and lines of the molding surrounding the doors and the formation of the edges of the doors of the front portion of the vehicle body shown in Fig. 1.

Fig. 3 is a front elevational view on reduced scale of the vehicle body shown in Fig. 1.

I claim:

The ornamental design for a vehicle body as shown and described.

CHARLES H. WIDMAN.
